His Attorney.

UNITED STATES PATENT OFFICE.

CHARLES H. BOECK, OF JACKSON, MICHIGAN.

DESIGN FOR AN OIL-STOVE.

SPECIFICATION forming part of Design No. 24,913, dated November 19, 1895.

Application filed July 22, 1895. Serial No. 556,836. Term of patent 7 years.

To all whom it may concern:

Be it known that I, CHARLES H. BOECK, a citizen of the United States, residing at Jackson, in the county of Jackson and State of Michigan, have invented and produced a new, original, and useful Design and Shape or Configuration for an Article of Manufacture—to wit, an Oil-Stove—of which the following is a specification, reference being had to the accompanying drawings, made part hereof, in which—

Figure 1 is a front elevation of a stove, showing my design; and Fig. 2 is an end elevation of the same, viewed from the right in Fig. 1.

Like numerals of reference indicate like parts in both views.

In the drawings, 1 is a supporting-frame. This frame, viewed in front elevation, presents two sections, rectangular in outline, the section at one end being longer and higher than the section at the other end, so that table or top 2, covering the longer higher section, and the table or top 3, covering the shorter and lower section, present the appearance of two steps in a stair. Within the longer and higher section of the supporting-frame are two vertical stove-bodies 4 4, symmetrically spaced in such section, and within the shorter and lower section of the supporting-frame and about centrally thereof is a single vertical stove-body 5 of a larger diameter than the stove-bodies 4 4. Each of these stove-bodies is cylindrical at bottom. The upper end of the cylindrical portions terminate in flaring rings 6, and are capped by conical frustum-shaped chimneys 7 7, having doors 8 8.

9 10 are oil tanks or reservoirs, substantially rectangular in outline, except that the front and rear edges are rounded in semicylindrical form, as clearly appears in Fig. 2. The tank 9 is horizontally disposed within the higher and longer section of the frame, and the

tank 10 is disposed in like manner within the shorter and lower section of the frame, the two tanks being arranged about centrally the height of their respective stove-bodies, and tank 9 being elevated above tank 10. The stove-bodies 4 4 pass vertically through tank 9, and stove-body 5 passes vertically through tank 10, the wick-chambers of the stove-bodies being in each case suitably connected with the interior of the respective tanks.

11 11 are rectangular diaphragms of sheet metal, horizontally disposed within the two sections of the frame and firmly secured at their corners and ends to the frame immediately above the oil-tanks above mentioned. These diaphragms serve the double purpose of shields between the combustion-chambers of the stove-bodies and the oil-tanks and as supports for the stove-bodies and tanks. In each of the two sections of the frame and immediately below the lower ends of the stove-bodies is a horizontal rectangular pan or shelf 12, of sheet metal secured to the frame. Immediately above each frustum-shaped chimney or cap is a grated opening 13 in the tops or tables 2 3.

The leading features of my design are the two-section frame, the two-step top or table, the stove-bodies of varying heights and sizes, the configuration of the two horizontal tanks having the stove-bodies passing therethrough, and the arrangement of the supporting diaphragms or shields.

What I claim as my invention, and desire to secure by Letters Patent, is—

The design for an oil stove, substantially as herein shown and described.

CHARLES H. BOECK.

In presence of—

JAMES W. DOW,
U. L. BADGLEY.
